DRESDEN, GERMANY

DEVICE FOR PROTECTING FILMS AGAINST IGNITION

Application filed March 27, 1930. Serial No. 439,353.

This invention relates to improvements in fire preventing devices, particularly devices for protecting the film of cinematographic projection apparatus against ignition in case **5** a break occurs in the film band.

It is the principal object of our invention to provide an automatically acting fire-preventing device of simple construction, yet efficient in its operation.

10 Another object of our invention is the provision of a fire-preventing device automatically protecting films against ignition as soon as the film band breaks between its feed roller and the film-way, and which is operated by **15** the enlarged loop formed by the film band in such cases.

Still another object of our invention is the provision of a device for protecting film bands of cinematographic apparatus against **20** ignition, with which means are connected to stop the motor as soon as the protecting device comes into play.

A further object of our invention is the provision of a film actuated device for guiding a protecting shield between window and light-cone as soon as a break in the film-band occurs and in which the movement of the shield will operate a switch controlling the motor operation, while suitable means are **30** provided to allow a resetting of the parts into their original operative position as soon as the break in the film band has been repaired.

A still further object of our invention is **35** the provision of a device of the above type equipped with a means preventing the ends of a broken film band to become entangled in the mechanism.

With these objects in view, our device principally consists of a protecting shield normally held inoperative through engagement by the nose of a lever adapted to be swung about its fulcrum as soon as a loop of abnormal size is formed in the film band due **45** to a break in the same which will engage and operate the lever to disengage its nose from the shield supporting arm to allow the swinging of the shield into its operative position while due to its connection with a motor control switch the operation of the shield will

operate this switch to stop the motor. A resetting of the parts can be conveniently effected by a suitable switch handle.

The ends of the broken film band are prevented from becoming entangled in the mechanism by means of a movable plate. **55**

These and other objects and advantages of our invention will become more fully known as the description thereof proceeds and will then be specifically defined in the appended claims. **60**

In the accompanying drawing forming a material part of this disclosure:

The single figure illustrates diagrammatically an automatically acting fire preventing device for protecting the films of cinematographic projection apparatus, constructed according to our invention. **65**

As illustrated, the film band 10 is guided about its feed roller 11, and forming a loop **70** 12 is guided in the usual manner through the film-guides or way 13.

If now the film band breaks and loop 12 in consequence thereof will assume abnormal proportions or size, as indicated in broken lines at 14, it will engage a curved flange 15 of a substantially triangular lever 16 fulcrumed at its apex, as at 17, to a part of the machine 18, and the loop will turn the lever about its fulcrum to disengage its nose 19 **75** 80 from the end 20 of one arm of a two-armed lever pivoted intermediate its ends, as at 21, the other arm of which carries at its outer end the protecting shield 22.

The pivot 21 carries also a roller 23 over which is guided an elastic band 24 or the like, secured at one end to the film guide and at its other end to the arm carrying the shield, and having the tendency to normally hold **85** end 20 in engagement with nose 19.

About a shaft 25 a switch, preferably a mercury switch, is turnable for starting and stopping the motor of the machine the lever 26 of which is connected by means of a bar **90** 95 or rod 27 or the like with the two armed lever 28.

In order to prevent the loop formed by the break in the film from entering between the feed roller 11 and the upper end 29 of lever **100**

15, a protecting plate 30 is movably arranged between both.

The device operates as follows:

Upon a break in the film 10 a comparatively large loop 14 will be formed as indicated in broken lines which will engage under the flange 15 of lever 16 and turn the same upwardly about its fulcrum 17. This movement will disengage nose 19 of this lever from the upper end 20 of the two-armed lever so that the same will now be turned about its pivot 21 by the pull of elastic bar 24 and will be swung into the position illustrated in broken lines in which the shield will come between window and light to protect the film.

Simultaneously by means of rod 27 the lever 26 of the switch 25 will be operated to stop the operation of the motor.

After the film has been repaired, an operation of lever 26 in the opposite direction will start the motor and bring the two-armed lever 28 back into its original position and the shield 22 will uncover the window tensioning band 24 while the lever 16 executing a downward movement will bring its nose 19 again in engagement with one end 20 of the two armed lever so as to set the device for another operation in case of a break in the film band.

The shield 30 will prevent the enlarged loop caused by the breaking of the film band from entering between feed roller and triangular lever.

It will be understood that we have disclosed the preferred form of our device only as one example of the many possible ways to practically construct the same, and that we may make such changes in its construction as come within the scope of the appended claims without departure from our invention and the principles involved.

Having thus described our invention what we claim as new and desire to secure by Letters Patent is:

1. A device for protecting the films in cinematographic projecting apparatus against ignition in case of a break in the film band forming an enlarged loop therein, comprising a substantially triangular lever fulcrumed in the machine at its apex, an upper curved flange on said lever adapted to be engaged by the enlarged loop to swing said lever about said fulcrum, a protecting plate movably connected to said lever for preventing the loose ends of the film band to become entangled in the mechanism, a two armed lever pivoted intermediate its ends, a nose on said triangular lever normally engaging the upper end of said two-armed lever adapted to be disengaged therefrom upon the operation of said triangular lever by said film band loop, a motor control switch and connections between said two-armed lever and the motor control switch to stop the motor as soon as a break in the film band occurs, and a movable protecting shield carried by the outer end of

one arm of said two-armed lever for protecting the film against ignition.

2. In a cinematographic projection apparatus including its motor, film band, feed roller and guide therefore, a protecting shield, a two armed lever pivoted intermediate its ends to one end of which said shield is secured, a means for normally holding said shield in its inoperative position, and a motor control switch connected with said shield supporting arm, means operated by the loop formed by a broken film band to release said shield holding means to swing said shield into its operative position between window and light and to operate said switch to stop the motor, a handle on said switch for allowing a resetting of the parts, and a movable protecting plate connected to said loop operated means to prevent the loose ends of a broken film from becoming entangled in the mechanism.

Signed at Dresden, Germany, this 4th day of March, A. D. 1930.
